19 Claims.

(Cl. 93—1)

The present invention relates to sheet assembling apparatus and more particularly to apparatus of this character which is adapted to assemble a plurality of sheets in groups so that 5 a portion of each sheet adjacent to one edge is exposed to receive a legend, the remainder of the surface of each sheet, except the top sheet, being covered. The number of sheets in a group may be varied to fit the particular purpose for 10 which the sheets are used. It is desirable also to be able to vary the width of the exposed portion of each sheet so that the legend may constitute one or more lines of data, as desired. It is desirable also that the apparatus operate effectively to produce unit strips composed of such 15 sheets wherein the size of the sheet itself may be varied by simple adjustment of the apparatus. The several sheets of each group or unit are secured to each other along one edge, preferably 20 an edge which is at right angles to the portions which are exposed.

The present invention has for its object the provision of an apparatus and method whereby a web of paper or like material may be cut off, 25 and assembled into unit strips comprising several sheets arranged in overlapping relationship. The apparatus preferably comprises means for advancing the web, means for cutting the web, and cooperating means for applying an adhesive to 30 secure the several sheets of a unit together and for finally arranging the sheets severed from the web in the desired overlapping relation.

One form of the invention is embodied in a machine having means to support and advance a 35 web of sheet material such as paper to an adhesive applying device which is adapted to periodically engage the web and apply adhesive thereto along a line adjacent to one edge of the ultimate sheet. The machine comprises also means for cutting the web between the several applications 40 of adhesive so as to form individual sheets. After the sheets are cut, an advancing and overlapping device arranges the several sheets in overlapped relation and discharges them from the machine. 45 The overlapping mechanism also preferably acts to secure one sheet to another by pressing the adhesive carrying portions thereof tightly together. The adhesive applying means is so arranged and controlled that without interruption 50 of the continuous operation of the machine the adhesive is periodically left off the web for a distance equivalent to the lengthwise extent of the sheet along the web.

The features and advantages of the present 55 invention will appear more fully as the descrip-

tion proceeds, reference being had to the accompanying drawings wherein a preferred form of the invention is shown. It is to be understood, however, that the drawings and description are illustrative only and are not to be taken as limiting the invention, except insofar as it is limited by the claims. 5

In the drawings,

Fig. 1 is a view in side elevation, with certain parts in section, illustrating the completed 10 machine;

Fig. 2 is an enlarged detail view of the removable counting wheel utilized in the mechanism shown in Fig. 1;

Fig. 3 is a fragmentary plan view illustrating 15 the assembling and overlapping mechanism;

Fig. 4 is an enlarged fragmentary view in side elevation of a portion of the overlapping mechanism;

Fig. 5 is a fragmentary sectional view taken 20 on the line 5—5 of Fig. 3;

Fig. 6 is a fragmentary sectional view taken on the line 6—6 of Fig. 3;

Fig. 7 is a sectional view taken on the line 7—7 of Fig. 3; 25

Fig. 8 is a fragmentary sectional view taken on the line 8—8 of Fig. 3 and showing the sheet gripping fingers in lowered position;

Fig. 9 is a sectional view taken on the line 9—9 of Fig. 4 illustrating the duplicate construction 30 at both sides of the machine;

Fig. 10 is an enlarged view in side elevation of the adhesive applying mechanism;

Fig. 11 is a view like Fig. 10 but with certain parts broken away and with the parts shown in 35 a different position;

Fig. 12 is a sectional view taken on the line 12—12 of Fig. 10;

Fig. 13 is a sectional view taken on the line 13—13 of Fig. 12; 40

Fig. 14 is a fragmentary sectional view taken on the line 14—14 of Fig. 10;

Fig. 15 is a fragmentary plan view of an assembled unit of strip sheets, and

Fig. 16 is a sectional view taken on the line 45 16—16 of Fig. 15.

Referring now in detail to the drawings, the present invention is embodied in and carried out by a machine of the general type hereinbefore described. The said machine is adapted to take 50 a web of paper 20 from any suitable source such as a roll and advance the same step by step by means of two feed rolls 21 and 22. The feed rolls 21 and 22 are journaled in two main side frames 23 and 24. Immediately following the feed rolls 55

in the direction of movement of the web 20 there are provided slitting knives 25 and 26 which are carried by suitable shafts 27 and 28 that are journaled in the side frames 23 and 24. The feed rolls 21 and 22 may be of any suitable form and may be driven in any suitable manner to provide the necessary step by step advancement of the web. As an example of a suitable drive mechanism for this purpose, the roll 22 is shown as provided with a sprocket wheel 29 which is driven by a sprocket chain 30. The sprocket chain 30 is adapted to be driven from a sprocket wheel 31 that is mounted on a shaft 32. The shaft 32 is journaled in the side frames 23 and 24. It also carries a gear wheel 33. The gear wheel 33 meshes with a rack 34 which is mounted to reciprocate in a guide 34a. The rack 34 is adapted to be driven from a shaft 35 by means of an arm 36. The rack is adjustably connected to the arm 36, a slot 37 being provided in the arm, and a pin 38 being provided on the rack for making this adjustment. The gear 33 is connected to the shaft 32 by means of a one-way drive connection or over-running clutch so as to drive the shaft 32 only on the downward stroke of the rack 34.

The shaft 35 is adapted to be driven by any suitable means, not shown, such for example, as an electric motor. This shaft is also adapted to operate a guillotine shear 40 by which the web is severed at the desired point. The shear comprises a lower knife supporting bar 41 having a knife 43 therein, an upper guide bar 43a, a knife supporting member 44 and an upper knife blade 45. The bar 44 is adapted to be actuated by means of two rods 46, one at each side of the frame of the machine. Each rod 46 is actuated by a lever 47 which is pivoted by a pin 48 to the adjacent side frame of the machine. The lever 47 carries a roller 49 which is adapted to engage a cam 50 on the shaft 35. Springs 51 hold the levers 47 in raised position. The guillotine shear 40 is a separate unit having its own standard or base 52 which is mounted adjacent to the ends of the side frames 23 and 24. The shaft 35 and the levers 47 are carried by laterally projecting brackets 53 on the standard 52.

The web 20 is adapted to be divided whenever it is wide enough to provide two or more sheets 50 by means of the slitters 25 and 26. These slitters are driven by gear wheels 54 and 55 which are fixed on the shafts 27 and 28 respectively. The gear 54 is driven by the gear 55 which is driven by a pinion 56 that is mounted on the side frame 23 by means of a stub shaft 57. The pinion 56 is driven by a gear 58 which is mounted on a stub shaft 59. The gear 58 meshes with a gear 60 which is fixed to a smaller gear 61 and a bevel gear 62. The gears 60, 61 and 62 are carried by a shaft 63 which is mounted in the side frame 23. These gears are adapted to be driven by a bevel gear 64 which is mounted on a main drive shaft 65 that extends alongside the machine and which is adapted to be operated from any suitable driving means.

The smaller gear 61 drives a gear 66 which is fixed to a cam 67, both being journaled on a shaft 68 that is mounted on the side frame 23. The cam 67 is adapted to actuate a lever 69 which, in turn, operates an adhesive applying mechanism 70.

The adhesive applying mechanism 70 is shown more fully and in detail in Figs. 10-14 inclusive. The adhesive applying mechanism comprises a glue pot 71 which is mounted on two brackets 72

and 73 which are, in turn supported by the side frames 23 and 24. The glue pot 71 is adapted to receive a supply of adhesive from a bottle 74 and may be suitably covered except where the bottle enters the same. The glue pot 71 contains an annular chamber 75 in which there is journaled an adhesive applying roller 76. The chamber 75 has a longitudinal slot 77 therein through which the roller 76 contacts two rollers 78 and 79 which are mounted on a shaft 80. The shaft 80 is, in turn, supported by two arms 81 and 82 that are carried by the brackets 72 and 73. The arms 81 and 82 are adjustable so as to vary the tension between the roller 76 and the rollers 78 and 79.

The roller 76 is mounted on a shaft 83 which has a sprocket wheel 84 thereon that is also driven by the sprocket chain 30 so as to continuously feed the glue from the glue pot 71 to the rollers 78 and 79. The mounting of the shaft 83 is so arranged with respect to the chamber 75 that at the upper edge of the opening 77 the wall of the chamber at 84 limits the amount of glue that can be carried over by the roller 76. At the lower edge of the opening 77 the wall 85 of the chamber is slightly spaced from the roller 76 so as to allow any excess of glue to accumulate and work to the center of the rollers 78 and 79 to return into the glue pot 71. Thus it is possible to maintain the glue pot and its contents substantially free of air circulation which would tend to harden the glue or adhesive used and make it necessary to empty the glue pot after each short run, if the machine were stopped for any period of time.

The glue pot 71 is held in place on the brackets 72 and 73 by means of clamps, one of which is indicated at 86 in Fig. 10. It will be understood that there is a similar clamp 87 at the opposite end of the cylindrical chamber 75. These clamps 86 and 87 are fastened to the brackets 72 and 73 respectively by bolts 88 that are in turn supported upon blocks 89, one at each side of the frame, the blocks being bolted to the brackets 72 and 73 respectively.

Referring now to the shaft 80, this shaft also serves to support two arms 90 and 91 which are fixed to the shaft to rock therewith. The rollers 78 and 79 are free to turn on the shaft since they must turn in response to their engagement with the roller 76. A lever arm 92 is clamped on the shaft 80 outside the bracket 72 so that by rocking the arm 92, the shaft 80 can be rocked as well. The arms 90 and 91 support a shaft 93, this shaft being journaled in the ends of the arms 90 and 91. An adhesive applying disc 94 is slidable endwise of the shaft 93 so it can be positioned at the proper spot with respect to the web 20. This disc has a hub 95 which is split and is adapted to be clamped on the shaft 93 by means of a bolt 96 (see Fig. 10).

Two arms 97 and 98 are mounted at the tops of the brackets 72 and 73 and extend outwardly over the arms 90 and 91. These arms, at their free ends, carry a shaft 99 which is free to rotate in the arms. On the shaft 99 there is provided a longitudinally adjustable disc 100 that is adapted to be set opposite the adhesive applying disc 94 so as to support the web when it is pressed upwardly by the disc 94. The disc 94 is moved upwardly into engagement with the web 20 at intervals by means of the cam 67 and the lever arm 69, which has a roller 69a riding on the cam 67. The lever 69 comprises two bars 101 and 102 which are pivotally mounted on a

post 103 that is secured in the side frame 23. The bars 101 and 102 support the roller 69a at their free ends. Intermediate the bars 101 and 102, two bars 104 and 105 are provided. These bars 104 and 105 are pivotally connected to each other by a pin 106. The openings in the bars 104 and 105 for the pin 106 are slightly elongated so as to permit relative swinging movement of the bars with respect to each other. A link 108 is bifurcated at its upper end and is secured to the bars 104 and 105 by the pin 106. A second link 109 is pivoted to the bar 104 intermediate its ends by a pin 110. The link 109 extends upwardly and connects to the free end of the lever arm 92. A spring 111 has one end connected to a pin 112 on the bar 102 and has its other end connected to a pin 113 on the side frame 23. This spring holds the roller 69a upon the surface of the cam 67.

20 During the time that the gluing disc 94 is applying adhesive to the web 20, the link 108 is stationary. Upon each rotation of the cam 67 the large circular part of the cam will move the lever 69 upwardly, thus causing the bar 104 to pivot around the pin 106 to lift the link 109 and cause the gluing disc 94 to engage the lower surface of the web 20. This position is shown in Fig. 10 of the drawings. As the roller 69a passes off the enlarged part of the cam 67, the lever 69 is permitted to drop, and the link 109 pulls down on the lever arm 92 to move the gluing disc 94 away from the web 20. The shape of the cam 67 will determine the period of engagement of the gluing disc with the web because the cam itself is driven at a constant rate and is preferably synchronized with the advance of the web 20. It is desirable to have the gluing disc 94 spread the adhesive along a line extending lengthwise of the web so that for each engagement of the disc with the web the line of adhesive is positioned at one side edge on the ultimate sheet which is a part of a unit strip, and the length of the adhesive is slightly less than the width of that part of the sheet which is not exposed after the sheets are overlapped.

As pointed out hereinbefore, it is a function of the present apparatus to periodically prevent the application of adhesive to a particular section of the web which will eventually become a sheet. This is necessary in order to break the series of overlapped sheets into units of the desired number of sheets. The control of the gluing disc 94 must be such, therefore, that it can be set to cause the gluing disc to skip an application after any predetermined number of applications from two to the largest practical number of sheets in a unit. Normally, this number would not be greater than twenty-five or thirty.

60 In the present apparatus, means are provided whereby to cause the gluing disc 94 to be withheld from the web at predetermined intervals. The means employed is a simple counting mechanism illustrated in side elevation in Fig. 1. A link 114 is pivoted to the gear wheel 66 which has a slot 115 therein adapted to receive a pin 116 for connecting the link 114 to the gear wheel. The slot 115 is for timing length of adhesive applied to the web relating to length of the sheet to be cut. A long sheet may be covered as much as eighty or ninety per cent while a short sheet may be covered only fifty or sixty per cent of total length. The link 114 connects to a bell-crank 117 that is pivoted on a stub shaft 118 carried by the side frame 23. The shaft 118 also 70 has a gear and ratchet wheel 119 thereon with

which a pawl 120 on the bell-crank 117 is adapted to engage. The pawl 120 directly engages the gear teeth of the wheel 119 so that no intermediate ratchet teeth are needed. The wheel 119 meshes with another gear wheel 121. The gear wheel 121 is mounted on a swinging arm 121a. The arm 121a is held in adjusted position by a bolt 122. This bolt is adjustable in a slot 122a in the frame. The gear wheel 121, in turn, meshes with a gear wheel 123 which is mounted on a shaft 124. The gear wheel 123 is connected to a notched disc 125 which is removably mounted on the shaft 124. The gear wheel 123 is secured to the disc 125 by readily removable screws which are indicated at 126. The disc 125 and 15 the gear 123 are both centered on the shaft 124.

The link 108 is connected at its lower end to a lever arm 128. The lever arm 128 is pivoted on a pin 129 that projects from the side frame 23, and is held down by a spring 130. The lever arm 20 128 has a tooth 131 which is adapted to engage in notches 132 that are provided in the disc 125. The normal direction of rotation of the gear wheels 119, 121 and 123 is as shown on the drawings in Fig. 1.

25 Each rotation of the gear 66 will cause the link 114 to rock the bell crank 117 and cause the pawl 120 to turn the gear wheel 119 a part of a revolution. The notches 132 are so arranged with respect to the discs 125 that, at 30 the end of the advance of the gear train, comprising the wheels 119, 121 and 123, by the pawl 120, one of the notches 132 may be aligned with the tooth 131 on the lever 128. When the tooth 131 drops into the notch 132, this causes the link 108 to move downwardly. This drops the pivot pin 106 downwardly and thus lowers the pivotal support of the bar 104. On the next reverse movement of the pawl 120, the cam 67 is so positioned as to be lifting the roller 69a. The lift imparted to the roller 69a is not sufficient, however, to cause the link 109 to raise the glue disc 94 into engagement with the web. This is because the drop of the link 108 has so lowered the pivotal support for the bar 104 as to prevent sufficient upward movement of the link 109 to raise the disc 94 the required distance. This position of the disc 94 is shown in Fig. 11.

35 When it is desired to change the number of sheets which will be connected in a unit strip, the gear 123 may be changed. That is, one gear 123 is removed and another one having a different number of teeth is substituted in its place. For example, the gears 123 are provided with different numbers of teeth, the smallest gear having eighteen teeth, and the largest gear having fifty teeth. If the operator desires to make groups with a small number of sheets, say seven, he uses a disc 125 having three notches and a gear 123 having twenty-one teeth. The same 40 gear will give groups of twenty-one with a disc 125 having only one notch.

45 When the sheets are cut by the blades 43 and 45, they already have the adhesive along one side edge. The length of the sheet is also already 50 determined. The remaining operation to be performed is the overlapping of the sheets the desired amount and pressing them together so as to cause them to adhere where the adhesive has been applied. Since the operation of the machine is continuous, the overlapping must be provided even where the adhesive has been left off, so as to divide the sheets into units of the required number. The overlapping mechanism is 55 shown most clearly in Figs. 1, and 3-9 inclusive. 75

The overlapping mechanism comprises two side frames 133 and 134 upon which a platform 135 is mounted. Over the platform 135 there is provided a cross bar or stop 136. The cross bar 136 is adapted to be moved up and down to receive and temporarily hold overlapped sheets. It acts also as a stop to maintain the sheets in alignment after they are cut from the web. The platform 135 which lies beneath the bar 136 is supported by the side frames 133 and 134. Two blocks 137 and 138 are bolted to the side frames 133 and 134. The platform 135 has pins 139 at its opposite ends, which pins are adapted to fit into corresponding holes 140 provided in the blocks 137 and 138 (see Figs. 3 and 7).

The cross bar 136 is carried by two adjustable arms 141 and 142 (see Figs. 3 and 8). The arms 141 and 142 are fixed on a rock shaft 143 which is journalled in the side frames 133 and 134. For purposes of adjustment, the arms 141 and 142 are made in two overlapping sections, as indicated in Fig. 3, and are adapted to be adjusted as to length and held in position by a plurality of bolts 144 and 145. Thus when the advance of the web by the feed rolls 21 and 22 is changed, the cross bar 136 is moved toward or away from the shear 40 so that the distance from the shear 40 to the bar 136 will equal the distance the web is advanced. The rock shaft 143 has a lever arm 146 secured thereto outside the frame 133. The lever arm 146 has a pin 147 thereon which pivots a block 148. The block 148 has an opening therein which receives a reduced portion 149 of a link 150. A spring 151 is mounted on the reduced portion 149 of the link 150 and is held under compression by a nut 152. The link 150 is adapted to raise the lever arm 146 by having the large portion thereof engage the block 148, but when the link 150 is pulled downwardly it pulls down on the lever arm 146 through the spring 151, thus giving a yielding downward pressure to the cross bar 136 in pressing it down upon sheets which build up between the cross bar 136 and the platform 135. Suitable means hereinafter more fully described are utilized to move the link 150 up and down.

A sheet advancing mechanism is provided whereby sheets which are cut off by the knives 43 and 45 may be advanced while the block 136 is raised. This sheet advancing mechanism comprises a horizontally movable plate 153 and spaced gripping elements 154 and 155 which are vertically movable with respect to the plate 153 so as to receive sheets therebetween and then grip the same. The gripping elements 154 and 155 move horizontally with the plate 153 so as to advance sheets gripped thereby. The plate 153 is supported by two sliding blocks 156 and 157 which are guided in grooves 158 and 159 that are provided in the side frames 134 and 133 respectively. The blocks 156 and 157 support the plate 153 by means of two screws 160 and 161. These screws also serve to connect two outwardly extending brackets 162 and 163 to the blocks 156 and 157. An additional screw 164 is used to secure each of the brackets 162 and 163 firmly to the blocks 156 and 157.

The brackets 162 and 163 serve to connect the sliding blocks 156 and 157 to means for reciprocating them. Two racks 166 and 167 are fastened to the lower surface of the brackets 162 and 163 immediately outside the side frames by screws 165. These racks mesh with segmental gears 168 and 169 which gears are fixed upon a rock shaft

170 which is journalled in the side frames 133 and 134.

The brackets 162 and 163 also carry depending guides 171 and 172 respectively. The guides 171 and 172 receive two rods 173 and 174 which are vertically slidable in the guides and which have elongated flat plates 175 and 176 at their lower ends. The rods 173 and 174 have reduced threaded upper ends 177 and 178 respectively. These threaded ends receive hollow internally and externally threaded screws 179 and 180 so that the screws 179 and 180 may be vertically adjustable with respect to the rods 173 and 174. Two supporting bars 181 and 182 extend toward each other from the screws 179 and 180 by which they are carried. These bars extend over the top of the side frames 133 and 134 and at their inner ends they are apertured to receive two supporting bolts 183 and 184. The bolts 183 and 184 are threaded into a cross bar 185 which carries the gripping elements 154 and 155. Suitable spacer bars, indicated at 186 and 187, are provided on the bolts 183 and 184. The spacer bars 186 and 187 and the bars 181 and 182 interlock in the manner shown so as to form a rigid supporting structure for the bar 185.

The bar 185 is pressed toward the plate 153 under yielding pressure at all times. For this purpose, two posts 188 and 189 are threaded into the plate 153 and project upwardly through the bar 185. Over the bar 185 these posts have coiled springs 190 and 191 thereon. The posts are threaded at their upper ends and are provided with nuts 192 and 193 so as to adjust the tension on the springs 190 and 191. The gripping elements 154 and 155 may be provided in any desired number, and they are longitudinally adjustable on the bar 185. It will be evident that lifting of the gripping elements 154 and 155 is accomplished by lifting the rods 173 and 174 against the tension of the springs 190 and 191 which at all times press the cross bar 185 downwardly.

Referring now more particularly to Figs. 1, 3 and 4 of the drawings, the mechanism whereby the rods 173 and 174 are periodically lifted in alternation with the up and down movement of the cross bar 136 comprises a rock shaft 194 which has two levers 195 and 196 at its opposite ends, the levers 195 and 196 being keyed to the shaft 194. The lever 196 extends forwardly beneath the rod 173 and carries a roller 197 which engages the plate 175. The lever 195 also carries a roller 198 which engages the plate 176 on the rod 174. The lever 195 has an extension 199 to which the link 150 is pivoted and by which both levers and the rock shaft 194 are actuated. A link 200 connects the extension 199 to a pin 201 on a driven gear 202. The gear 202 is driven from another gear 203. The gears 202 and 203 are journalled on suitable shafts 204 and 205 respectively which are mounted in the side frame 133. The gear 203 meshes with a gear 206 which is fixed to a bevel gear 207 that engages a bevel gear 208 on the drive shaft 65. For each rotation of the gear 202, the rock shaft 194 will complete one cycle of rocking movement so as to alternately raise and lower the cross bar 136 and the gripping elements 154 and 155.

The rock shaft 170 is driven from the gear 203 in timed relation to the operation of the rock shaft 194. An arm 209 depends from the hub of the segmental gear 169. An arcuate bar 210 is bolted to the arm 209 and is adapted to receive and adjustably support one end 211 of a link 212.

The other end of the link 212 is journalled on a pin 213 which is fixed on the gear 203. It will be appreciated that the adjustment of the end 211 of the link 212 along the arcuate bar 210 will vary the stroke imparted to the arm 209 by each rotation of the gear 203. As the distance through which the arm 209 moves is changed, the distance through which the racks 166 and 167 travel is also changed. This, in turn, changes the longitudinal movement of the plate 153 and the mechanism carried by the blocks 156 and 157.

In Figs. 15 and 16 a pair of overlapped sheets 20a are shown. The exposed part of each sheet is indicated at 20b. A line of adhesive 20c is shown in its preferred position with respect to the adjacent edges of the sheets.

The operation of the machine will now be described. Initially, the operator will set the travel of the rack 34 so as to impart the desired step by step advance of the web 20 by the step by step movement given to the sprocket chain 30. The operator will also set the cross bar 136 so that its distance from the shear 40 is substantially equal to the distance the web advances on each stroke. The adhesive applying mechanism 10 and the cooperating counting mechanism associated therewith will be set to apply the adhesive to the desired number of successive sheets. This is accomplished by using the correct combination of gear 123 and disc 125 to actuate the lever arm 128. The link 212 will be adjusted with respect to the bar 210 so as to give the desired amount of overlap by controlling the reciprocation of the guide blocks 156 and 157. When the machine is started in operation, each advance of the web 20 will be followed by a cutting operation by the shear 40. The sheet which is sheared off will have first been pushed through the shear to engagement with the cross bar 136 while this bar is in its "down" position. This bar is then lifted by means of the link 150 and at the same time the gripping elements 154 and 155 are lowered into engagement with the sheet. These gripping elements are supported by the blocks 156 and 157 and advance the gripped sheet while the cross bar 136 is raised. At the end of their travel, the gripping elements release the sheet and the cross bar 136 presses down upon it.

The cycle of operation continues, with each cut sheet being laid upon the preceding sheet and both of them advanced. There is no interruption of the process in order to divide the overlapped stream of sheets into a number of units. This automatically occurs due to the fact that the adhesive applying mechanism 10 skips a sheet at the desired intervals, and of course that sheet will not stick to the preceding sheets that have been overlapped.

The line of overlapped sheets, in passing from the machine, is guided over an inclined plate 214 which overlies the upper end of a second inclined plate 215. A spacer 216 determines the drop from the plate 214 to the plate 215. Near the lower end of the plate 215 there is arranged an adjustable stop 217 which may be moved toward or away from the spacer 216. The distance between the spacer 216 and the stop 217 is set to be slightly more than the total length of a unit strip. As each unit strip strikes the stop 217 its rear end will drop below the lower end of the plate 214 and allow the next unit strip to slide over the top thereof. In this fashion, the several strips can be piled on the plate 215 and removed at intervals by the operator.

While I have shown and described one form of

my invention, it is to be understood that it is capable of many modifications. Changes, therefore, in the construction and arrangement may be made without departing from the spirit and scope of the invention as described in the appended claims, in which it is my intention to claim all novelty inherent in my invention as broadly as possible, in view of the prior art.

I claim:

1. A machine of the character described adapted to produce units of sheets wherein each sheet overlapped with respect to the adjacent sheets and wherein the several sheets are temporarily secured together, said machine comprising a web advancing means, adhesive applying means adapted to apply adhesive at spaced intervals to said web, a cutting device adapted to cut the web into sheets of the desired size, and means receiving the cut sheets from said cutting device, said last named means being operable to move the sheets away from the cutting device step by step whereby succeeding sheets are overlapped with previously cut sheets.

2. A unit strip machine comprising a web advancing device, a device adapted to apply adhesive lengthwise of said web at spaced intervals thereon, control means operable to prevent application of adhesive to the web for one of said intervals after a predetermined number of intervals, means to cut said web between the lines of adhesive, and overlapping means for arranging the sheets formed thereby in overlapped relation.

3. A unit strip machine comprising a web advancing device, a device adapted to apply adhesive lengthwise of said web at spaced intervals thereon, control means operable to prevent application of adhesive to the web for one of said intervals after a predetermined number of intervals, means to cut said web between the lines of adhesive, and overlapping means for arranging the sheets formed thereby in overlapped relation, said overlapping means including a stop member for engaging the advancing ends of the sheets as they are cut from the web.

4. A unit strip machine comprising a web advancing device, a device adapted to apply adhesive lengthwise of said web at spaced intervals thereon, control means operable to prevent application of adhesive to the web for one of said intervals after a predetermined number of intervals, means to cut said web between the lines of adhesive, and overlapping means for arranging the sheets formed thereby in overlapped relation, said overlapping means comprising a stop member for aligning the cut sheets, gripping means operable to grip several sheets of a unit and advance the same, said gripping means and said stop means being alternately in position to hold the several sheets of a unit together.

5. A machine of the character described adapted to produce units of sheets wherein each sheet is overlapped with respect to the adjacent sheets and wherein the several sheets are temporarily secured together, said machine comprising a web advancing means, a cutting device adapted to cut the web into sheets of the desired size, and adhesive applying means adapted to apply adhesive lengthwise of the web at spaced intervals.

6. A unit strip machine comprising a web advancing device, a device adapted to apply adhesive lengthwise of said web at spaced intervals thereon, control means operable to prevent application of adhesive to the web for one of said intervals after a predetermined number of inter-

vals, means to cut said web between the lines of adhesive, and overlapping means for arranging the sheets formed thereby in overlapped relation, said control means being operable to vary said predetermined number of intervals.

7. In a machine of the character described adapted to produce units of sheets wherein each sheet is overlapped with respect to the adjacent sheets and wherein the several sheets are temporarily secured together, an aligning and holding member, means to feed sheets to said member, a sheet advancing clamp adapted to grip sheets held and aligned by said first named member, and means to close and advance said clamp when the first named member is released from the sheets.

8. A machine of the character described adapted to produce units of sheets wherein each sheet is overlapped with respect to the adjacent sheets and wherein the several sheets are temporarily secured together, said machine comprising a web advancing means, adhesive applying means adapted to apply adhesive at spaced intervals to said web, a cutting device adapted to cut the web into sheets of the desired size, means receiving the cut sheets from said cutting device, said last named means comprising a holding member adapted to hold several sheets together in overlapped position to receive a freshly cut sheet in overlapped relation to the held sheets, and a clamping and advancing member operable to clamp the freshly cut sheet to the held sheets whereby to cause adherence of the sheets having adhesive between them, said last named member being operable to feed the sheets clamped thereby to the holding member.

9. A machine of the character described adapted to produce units of sheets wherein each sheet is overlapped with respect to the adjacent sheets and wherein the several sheets are temporarily secured together, said machine comprising a web advancing means, adhesive applying means adapted to apply adhesive at spaced intervals to said web, a cutting device adapted to cut the web into sheets of the desired size, and means receiving the cut sheets from said cutting device, said last named means comprising gripping members alternately gripping said sheets, one member engaging and holding previously cut sheets stationary while a sheet is being cut, and the other member engaging and advancing the newly cut and previously cut sheets.

10. A machine of the character described adapted to produce units of sheets wherein each sheet is overlapped with respect to the adjacent sheets and wherein the several sheets are temporarily secured together, said machine comprising a web advancing means, adhesive applying means adapted to apply adhesive at spaced intervals to said web, a cutting device adapted to cut the web into sheets of the desired size, means receiving the cut sheets from said cutting device, said last named means comprising gripping members alternately gripping said sheets, one member engaging and holding previously cut sheets stationary while a sheet is being cut, and the other member engaging and advancing the newly cut and previously cut sheets, and means to vary the advancing movement of said last named member.

11. A unit strip machine comprising a web advancing device, a device adapted to apply adhesive lengthwise of said web at spaced intervals thereon, control means operable to prevent application of adhesive to the web for one of said intervals after a predetermined number of in-

ervals, means to cut said web between the lines of adhesive, overlapping means for arranging the sheets formed thereby in overlapped relation, said last named means comprising gripping members alternately gripping said sheets, one member engaging and holding previously cut sheets stationary while a sheet is being cut, and the other member engaging and advancing the newly cut and previously cut sheets.

12. A unit strip machine comprising a web advancing device, a device adapted to apply adhesive lengthwise of said web at spaced intervals thereon, control means operable to prevent application of adhesive to the web for one of said intervals after a predetermined number of intervals, means to cut said web between the lines of adhesive, overlapping means for arranging the sheets formed thereby in overlapped relation, said last named means comprising gripping members alternately gripping said sheets, one member engaging and holding previously cut sheets stationary while a sheet is being cut, and the other member engaging and advancing the newly cut and previously cut sheets, and means to vary the advancing movement of said last named member.

13. A unit strip machine comprising a web advancing device, a device adapted to apply adhesive lengthwise of said web at spaced intervals thereon, control means operable to prevent application of adhesive to the web for one of said intervals after a predetermined number of intervals, means to cut said web between the lines of adhesive, overlapping means for arranging the sheets formed thereby in overlapped relation, said last named means comprising gripping members alternately gripping said sheets, one member engaging and holding previously cut sheets stationary while a sheet is being cut, and the other member engaging and advancing the newly cut and previously cut sheets, said control means being operable to vary said predetermined number of intervals.

14. A unit strip machine comprising a web advancing device, a device adapted to apply adhesive lengthwise of said web at spaced intervals thereon, control means operable to prevent application of adhesive to the web for one of said intervals after a predetermined number of intervals, means to cut said web between the lines of adhesive, overlapping means for arranging the sheets formed thereby in overlapped relation, said last named means comprising gripping members alternately gripping said sheets, one member engaging and holding previously cut sheets stationary while a sheet is being cut, and the other member engaging and advancing the newly cut and previously cut sheets, said control means being operable to vary said predetermined number of intervals.

15. A method of producing units of sheets from a web wherein each sheet is overlapped in one direction with respect to adjacent sheets, and wherein the several sheets are secured together, said method comprising the application of adhering means at points spaced lengthwise of the web, severing of the web into sheets carrying said adhering means, and stacking said sheets one upon another as they are severed, and advancing the stacked sheets the amount of overlap after each sheet is severed and before the next sheet falls on the stack.

16. A method of producing units of sheets from a web wherein each sheet is overlapped in one direction with respect to adjacent sheets, and

wherein the several sheets are secured together along a line parallel to the direction of overlapping of the sheets, said method comprising the application of adhesive material to one side of the web adjacent one longitudinal edge thereof, severing the web into sheets, stacking said sheets one upon another as they are severed, and advancing the stacked sheets the amount of overlap after each sheet is received.

10 17. A method of producing units of sheets from a web wherein each sheet is overlapped in one direction with respect to adjacent sheets, and wherein the several sheets are secured together along a line parallel to the direction of overlap-

15 ping of the sheets, said method comprising the application of adhesive material to one side of the web adjacent one longitudinal edge thereof, leaving the adhesive off of a sheet length of web at predetermined intervals lengthwise of the web, 5 severing the web into sheets, stacking the sheets 20 one upon another as they are severed, and advancing the stacked sheets the amount of overlap after each sheet is received.

18. A method of producing units of sheets from 25 a web wherein each sheet is overlapped in one direction with respect to adjacent sheets, and wherein the several sheets are secured together along a line parallel to the direction of overlap-

ping of the sheets, said method comprising the application of adhesive material to one side of the web adjacent one longitudinal edge thereof, leaving the adhesive off of a sheet length of web at predetermined intervals lengthwise of the web, 5 severing the web into sheets, stacking the sheets one upon another as they are severed, and advancing the stacked sheets the amount of overlap after each sheet is received, feeding said overlapped sheets over a ledge and against a stop 10 spaced from said ledge whereby the last sheet of each unit may drop from the advance sheet of the next unit, and thereby stacking the units one upon another.

19. A method of producing units of sheets from 15 a web wherein each sheet is overlapped in one direction with respect to adjacent sheets, and wherein the several sheets are secured together along a line parallel to the direction of overlap- 20 ping of the sheets, said method comprising severing the web into sheets, stacking said sheets one upon another as they are severed, advancing 25 the stacked sheets the amount of overlap after each sheet is received, and securing said overlapped sheets to each other in units of a predetermined number of sheets.

CHRISTIAN PAULSEN.
